UNITED STATES PATENT OFFICE.

WILLIAM F. HENDRY, OF OSSINING, AND CHARLES J. NELSON, OF NEW YORK, N. Y.,
ASSIGNORS, BY MESNE ASSIGNMENTS, TO NATIONAL CARBON COMPANY, INC., OF
NEW YORK, N. Y., A CORPORATION OF NEW YORK.

FLASH LIGHT.

Application filed April 14, 1925. Serial No. 22,960.

This invention relates to flashlights and more particularly to new and useful improvements in circuit-controlling switches adapted for use with flashlights.

5 It is the object of the present invention to provide a flashlight switch of simple and inexpensive construction and one by means of which the light may be flashed, permanently lighted, or locked out of circuit.

10 With this object in view the flashlight is provided with a slide adapted for movement into three distinct operating positions. In the first position the slide is out of contact with a conductor through which the lamp circuit may be completed; in the second position it is normally out of contact with the conductor but may be momentarily pressed into engagement therewith; and in the third position the slide is permanently bearing against the conductor. The slide is maintained in its various positions by means of a spring fastened to the flashlight casing and bearing against a corrugated face of the slide. This spring serves also for the purpose of permitting the use of the slide as a push button in its second position.

15 These and other features of the invention will more readily appear from the following detailed description of an embodiment thereof and the appended claims.

20 In the drawings, Fig. 1 is a vertical cross-section of the flashlight structure with the switch in its normal locked position; Fig. 2 is a vertical cross-section of the switch in its flashing position; Fig. 3 is a similar view of the switch in its actuated position; and Fig. 4 is a perspective view of the switch mechanism and cooperating spring contacts.

25 The flashlight comprises a metallic casing 1 containing the dry cells 2 surrounded by an insulating wrapper. The carbon electrode 3 of the top dry cell is pressed against one terminal 4 of an incandescent light bulb 5 by means of a coiled spring 6. The coiled spring is held under compression between the bottom of the lowermost dry cell and a cap 7, which screws on the open lower end of casing 1. The second terminal of the lamp 5 is connected in the usual manner with a screw-threaded base 8 held in a socket 9. The socket is mounted in a metallic reflector 10 and serves the purpose of insulating the base 8 from the reflector 10 and for connect-

ing it with a metallic disc 11 mounted below an insulating disc 12 held between the socket 55 9 and the lower end of the reflector 10. The reflector is surrounded by a bell-shaped casing 13 which is in screw-threaded engagement with the upper end of the tubular casing 1. The flaring end of casing 13 is closed 60 by means of the usual glass lens 14 held thereto by means of a ring 15. Of course, the present switch is adapted for use with a large variety of reflector and lamp arrangements. 65

70 The circuit of lamp 5 is established through terminal 4, the carbon terminal 3 of the uppermost dry cell, thence through the dry cells, the zinc terminal of the lowermost dry cell, coiled spring 6, cap 7 and metallic casing 1. From this point the current flows through a spring 20 riveted near one of its ends to casing 1 at 21. Near its center point the spring 20 is bent down so that its free end lies in a lower plane than the end riveted to the casing 1, but still substantially parallel with the casing. The end of the spring 20 is bent into a nose shape and presses against a metallic strip 23 carried on a metallic slider 24, constituting a raised portion 80 thereof. A button 25 protruding from the slider 24 projects through a longitudinal slot 26 cut in the casing 1. The slot 26 is long enough to permit longitudinal displacement of the slider 24 within the casing, the 85 limits of said displacement being determined by the relative sizes of the slot 26 and the button 25. When the button 25 is in its lowermost position then the lamp can not be lighted; when it is in its intermediate position then the lamp may be flashed; 90 and when in its top position, then the lamp is permanently lighted.

95 The other terminal of the lamp 5 is, as above stated, connected through the base 8 with the disc 11. This disc is in engagement with the bent end 27 of a flat spring 28. Except for its bent end 27 and its other end 29, also slightly bent, the spring 28 is surrounded by means of an insulating wrapper 30, 100 and the spring with the insulation is fastened to the inside of the tubular casing by means of rivets 31, 32 which, by virtue of the relatively large holes provided in the spring 28, do not conductively connect the 105 latter with the casing.

The free end of spring 20 presses the slider 24 against the inside surface of the tubular casing 1. The metallic strip 23 fastened to the bottom of the slider is formed with three corrugations 33, 34 and 35. When the slider is in its lowermost position, the nose 22 of the spring 20 rests within the corrugation 33. When the button 25 is pressed down with the slider 24 against the tension of spring 20, then, as clearly illustrated in Fig. 1, the metallic slider 24 will clear the lower free end 29 of spring 28, whereby the circuit for the lamp 5 will not be completed. If it is desired to flash the lamp, then, by means of the button 25, the slider 24 is moved upward into an intermediate position in which, as shown in Fig. 2, the end 22 of spring 20 rests on the corrugation 34. The circuit for the lamp still remains open at the lower free end 29 of spring 28. However, when the button 25 is now depressed, then the edge of the slider 24 will engage the spring end 29 and thus complete the circuit for the lamp 5. In response to each depression of the button 25, the lamp will be lighted and when the button is released, the lamp will be extinguished.

If it is desired permanently to light the lamp 5, then the slider 24 is moved by means of the button 25 into its uppermost position in which the upper end of the metallic strip 23 presses against the free spring end 29, the two lying in each other's paths. In this position of the switch the nose 22 rests in the lowermost corrugation 35 and holds the switch in its advanced position, the circuit for the lamp being completed through the metallic strip 23, the spring 20 and the casing 1.

In order to prevent the battery 2 from pressing spring 29 into contact with the slide, flanges 36 are provided on the latter to maintain the battery at a distance from the spring. It will be noted also that the lower part of spring 20 is so shaped that the battery inserted through the rear of the casing will readily slide in place.

What we claim is:

1. In a flashlight, a casing, a battery and a lamp enclosed therein, a circuit for said lamp including a contact member and a slide having an uneven surface, said slide and contact member being enclosed within said casing in different planes and normally spaced from each other, a button for moving said slide projecting to the outside of said casing, and resilient means engaging the uneven surface of said slide.

2. In a flashlight, a metallic casing, a battery and a lamp enclosed therein, a circuit for said lamp including a corrugated slide and a contact member, said slide and contact member being enclosed within said casing in different planes and normally spaced from each other, a button for moving said slide

projecting to the outside of the casing, and resilient means engaging the corrugations on said slide.

3. In a flashlight, a casing, a battery and an incandescent lamp within said casing, a connection between one terminal of said lamp and one electrode of said battery, a metallic slide having a raised portion and provided between said battery and the side wall of said casing, a button projecting from said slide to the outside of said casing and by means of which said slide may be moved longitudinally and laterally with respect to said casing, a connection between said slide and the other pole of the battery, and a conductor having one end in contact with the other terminal of said lamp and another end in cooperative relation with said slide, said other end lying in the path of said raised portion and below the plane of the body of said slide.

4. In a flashlight, a casing, a battery and an incandescent lamp within said casing, a connection between one terminal of said lamp and one electrode of said battery, a metallic slide provided between said battery and said casing, a button projecting from one face of said slide through a slot to the outside of said casing, a strip of metal having three corrugations fastened to the opposite face of said slide, a spring fastened to said casing and having a free end bearing against said corrugations, a conductor having one end in contact with the other terminal of said lamp and the other end in cooperative relation with said slide and strip, said other end lying in the path of said strip and below the plane of said slide.

5. In a flashlight, a tubular casing, a battery and an incandescent lamp within said casing, a connection between one terminal of said lamp and one electrode of said battery, a connection between the other electrode of said battery and said casing, a metallic slide provided between said battery and said casing, a button projecting from one face of said slide through a longitudinal slot to the outside of said casing, a strip of metal having three corrugations fastened to the opposite face of said slide, a flat spring fastened to said casing and having a free resilient end bearing against said corrugations, and another flat spring fastened to said casing but insulated therefrom and having one end in contact with the other terminal of said lamp and the other end in cooperative relation with said slide and strip, said other end lying in the path of said strip and below the plane of said slide.

6. In a dry battery flashlight, a metallic casing, a lamp having one terminal connected with one electrode of the battery, a connection between the other electrode of the battery and said casing, a metallic slide within said casing, a button for moving said

- slide projecting to the outside of said casing through a relatively long slot therein, said slide being large enough to cover the slot in the lowermost, intermediate and topmost positions of said button and slide, three corrugations in the lower face of said slide, a spring fastened to said casing and having a free end lying in one of said corrugations depending on the position of said slide for pressing the slide against the inside surface of said casing; and a contact spring fastened to but insulated from said casing and having one end connected to the other terminal of said lamp and the other end so positioned that it lies above the upper edge of said slide when the latter is in its lowermost position, opposite the upper edge of said slide but normally out of contact therewith when the slide is in its intermediate position and permanently in contact with said slide when it is in its topmost position.
7. In a dry battery flashlight, a tubular metallic casing, a lamp having one terminal connected with one electrode of the battery, a connection between the other electrode and said casing, a metallic slide within said casing, a slide actuating button projecting to the outside of said casing through a relatively long slot therein, said slide being large enough to cover the slot in the lowermost, intermediate and topmost positions of said button and slide, a strip of metal having three corrugations projecting from the lower face of said slide, a spring fastened to said casing and having a free end lying in one of said corrugations depending on the position of said slide for pressing the slide against the inside surface of said casing; a contact spring fastened to but insulated from said casing having one end connected to the other terminal of said lamp, and the other end so positioned that it lies above the upper edge of said slide when the latter is in its lowermost position opposite the upper edge of said slide but normally out of contact therewith when the slide is in its intermediate position and permanently in contact with said strip of metal when the slide is in its advanced position.
8. In a flashlight, a casing, a lamp and a battery in said casing, means including a longitudinally and laterally movable slide in said casing for controlling the lamp circuit, and two flanges on said slide for holding the battery at a distance therefrom.
9. In a flashlight, a casing, a lamp and a battery in said casing, a slide, a contact spring, an actuator for moving said slide longitudinally and laterally with respect to said contact spring for controlling the lamp circuit, and two longitudinal flanges projecting from said slide for holding said battery at a distance from said spring.
10. In a flashlight, a metallic casing, a battery and a lamp enclosed therein, a contact member in the circuit of said lamp mounted on said casing but insulated therefrom, a slide within said casing, means for moving said slide into any one of three positions, in the first one of which it is out of the range of said member, in the second out of contact but in cooperative relation with said member, and in the third in contact with said member, and a spring mounted on and electrically connected with the casing pressing said slide against said casing.

In testimony whereof, we have signed our names to this specification this 9th and 10th day of April 1925.

WILLIAM F. HENDRY.
CHARLES J. NELSON.
